APPARATUS FOR PRODUCING COMPOSITE
METAL ARTICLES

Robert K. Hopkins, New York, N. Y., assignor
to M. W. Kellogg Co., New York, N. Y., a corporation of Delaware

Application August 26, 1938, Serial No. 226,861

9 Claims. (Cl. 22—58)

This invention relates to the manufacture of metal articles and in particular to a method, and apparatus for carrying it out in practice, for forming metal bodies by the union of molten metal to solidified metal.

This application is a continuation in part of my application filed December 30, 1937, Serial No. 182,461.

In my prior application, above noted, I have disclosed the manufacture of ingots, slabs, and similar metal bodies by the union of molten metal to solidified metal. To secure a complete union throughout between the molten metal and the solidified metal, electric current is discharged in the region of the juncture of the metals to melt a depth of the solidified metal so that fused metal is presented to the molten metal for union therewith. This result is obtained by employing one or more movable electrodes and so controlling their movement that a fused surface is constantly presented to the rising molten metal and complete union is uniformly obtained. To assure a complete union the molten metal, as well as the electric discharge, is maintained under a blanket of flux which may initially be solid or molten.

In order to operate the novel method successfully it is necessary that the electric discharge bear a constant position relation with respect to the rising level of the molten metal. I accomplish this by raising the electrode, or electrodes, and its, or their associated operating means with the rising level of the molten metal. This application is particularly directed to this feature of the invention.

It is, therefore, the primary object of this invention to provide a method for forming metal bodies, and a novel apparatus for carrying the method out in practice, in which molten metal is united to solidified metal by electrical discharge from the end of an electrode; the novel method and apparatus being such that a constant positional relation is maintained between the end of the electrode and the surface of the molten metal.

The above as well as the further objects and advantages of the invention will be better understood from a consideration of the following description, of present preferred modes of carrying the invention out in practice, taken with the accompanying drawings, in which,

Fig. 1 is a schematic view, partly in section of apparatus particularly suited for carrying out the invention in practice,

Fig. 2 is a side sectional view of Fig. 1,
Fig. 3 is a fragmentary section view similar to

Fig. 2 illustrating a modified form of the apparatus.

The novel method of this invention may be employed in the manufacture of metal bodies of substantially uniform composition throughout or it may be employed in the manufacture of composite bodies that include a base of one composition with one or more coatings of different composition, or different compositions. The bodies as manufactured may be in the form of finished articles or they may be in the form of intermediate articles or workpieces such as ingots, slabs, billets, cylinders and the like, from which final articles may be produced by working operations such as forging, rolling, etc. The final articles may be produced in the form of flat members such as slabs, plates, etc., or shaped members such as angles, channels and similar shaped forms, or they may be produced as solid cylinders such as bars or hollow cylinders such as tubes.

The novel method of the invention is particularly applicable to the manufacture of bodies, such as ingots, of substantially uniform composition that include an outer shell of metal, work refined or cast, to which is united a core of cast metal; the metal defining the outer surface of the shell being in such condition and free from imperfections to such a degree that the body may be worked directly as formed. It is particularly advantageous to form alloy ingots, such as chrome steel, chrome-nickel steel, etc., in this manner as the amount of metal removed and the labor employed in removing imperfections in the surface of alloy ingots preparatory to working are excessive.

The novel method of this invention may also be used in the manufacture of coated articles of different sorts and of a wide range of compositions. The base metal may be carbon steel, iron or any of the metals and alloys commonly used in the manufacture of machines, apparatus, vessels, containers, structural members, etc. The cast metal may be of any ferrous or non-ferrous metals or alloys such as chrome steel, manganese steel, chrome-nickel steel, Monel metal, etc., having corrosion, or oxidation, or wear, or other resisting property superior to that of the chosen base metal in the intended service. The composite articles produced by my novel method, being unitary structures are admirably suited to withstand the severest service conditions, as for instance, those encountered in the petroleum processing arts where corrosive mediums are handled at temperatures in excess of 1000° F. and under pressures in excess of 1000 lbs. per square

inch. The preferred base metal for this class of service will usually be plain carbon steel or low chrome-molybdenum-carbon steel; the coating metal for this class of service will usually be chrome steel, chrome-nickel steel, Monel metal, etc.

By depositing molten base metal within a solidified shell of alloy a composite body may be formed which can be used as such or can be converted by well known working operations into outside lined bars, rods and tubes. When the molten base metal is deposited around a solidified alloy core a body is produced which can be worked into internally lined tubes. By depositing molten base metal between concentric solidified alloy shells, tubes that are lined both inside and outside may be produced. By depositing molten base metal against one face of an upright or substantially upright sheet, plate or slab of solidified alloy a slab is produced which can be worked in a well known manner to produce lined sheets or plates. If the molten base metal is deposited between two such alloy sheets, plates, or slabs the resulting body can be converted into sheets or plates both major surfaces of which are defined by alloy.

In all of the above cases it should be evident that when desired or advantageous the base metal may be in the solidified condition and the alloy deposited as molten metal.

To carry out my novel method the solidified metal is placed in a mold which, though not necessarily, is preferably arranged to be cooled by the circulation of a heat exchange medium, such as water. The solidified metal is so positioned that its surface, or surfaces, to which the molten metal is to be united is disposed angularly to the horizontal.

For best results a flux blanket is then deposited in the bottom of the mold of sufficient depth to submerge the current discharge, the molten metal, and the zone adjacent the juncture of the solidified metal and the molten metal. The flux not only protects the operation from the atmosphere, but by reason of its heat retaining character and its effect on the current discharge assures a thorough union throughout between the metals. The flux may be molten or solid as placed in the mold and quantities of it may be added as required during the operation.

The flux should be such that it will not liberate deleterious gas, either as to quantity or kind, under the conditions of the operation. The flux, furthermore, should not remove substantial quantities of desirable ingredients from the molten metal or add substantial quantities of undesirable ingredients to the molten metal but must flux out impurities. Silicates in general, either simple or complex, or mixtures of silicates are satisfactory. Aluminates, titanates, and similar compounds are also satisfactory and may be used alone or in mixture with silicates. The flux may also include thinning compounds such as feldspar, and the like. The flux may consist of prefused reacted ingredients or of calcined, sintered or dried unreacted ingredients. At present, silicates of the alkaline earths, calcium and magnesium being most commonly used, and the silicates of manganese, aluminum and iron are preferred as fluxes.

After the flux blanket has been laid the molten metal is deposited in the mold beneath the blanket of flux so that it will rise against the surface of the solidified metal to which it is to be united. The molten metal may be supplied

from various sources. Thus, it may be supplied from a ladle, by either top or bottom pouring, or it may be supplied from one or more consumable electrodes of proper composition, or it may be supplied in part from one of these sources and in part from the other.

Shortly before, or concurrently with, or shortly after, the deposition of the molten metal is begun electric current is discharged from the end of an electrode, or electrodes, to the region of the juncture of the metals to fuse a depth of the solidified metal and to supply sufficient heat to the adjacent molten metal to assure a complete union of the metals. This electrode, or electrodes, may be non-consumable or consumable. If consumable it is preferably of substantially the same composition as the molten metal. This electrode, or electrodes, is angularly disposed to both the solidified metal surface and the molten metal surface and may discharge against both at their juncture or against one or the other adjacent their juncture. It is necessary, however, that the discharge be so located that a sufficient depth of the solidified metal be fused and sufficient heat supplied to the molten metal to assure the thorough union of the metals.

Since a thorough union is desired throughout, it is necessary that substantially the whole of the surface of the solidified metal, to which the molten metal is to be united, be subjected to the influence of the electric discharge. This is accomplished by affecting such relative movement between the electrode, or electrodes, and the surface that there is constantly presented a substantially continuous band of fused surface metal in the region of the level of the rising molten metal. When a single electrode is employed, or when a plurality of electrodes are employed that are not closely enough spaced to overlap the areas fused by them, the relative movement will include a lateral as well as a vertical component. When a plurality of electrodes are employed sufficiently closely spaced so that the areas fused by them overlap the relative movement need only include a vertical component.

To obtain satisfactory results it is generally necessary, or at least desirable, that a substantially uniform depth of the solidified metal be fused. In some cases this result may be obtained by merely maintaining the electric discharge constant, in other cases cooling is additionally required, while in still other cases it may be necessary to vary the energy of the discharge as the operation progresses.

Since the surface fusing electrode, or electrodes, is angularly disposed relative to both the solidified surface and the molten surface and the molten surface is constantly rising it is necessary to raise the discharge end of the electrode, or electrodes, with the rising molten metal in order to maintain an electric discharge of predetermined character between the electrode, or electrodes, and a predetermined point or zone of the metal surface or surfaces. This may be accomplished in various ways. Thus, when the mold is of constant cross section the electrode, or electrodes, may be raised at the rate of rise of the molten metal. A more satisfactory way of accomplishing this result, and the way that is at present preferred is to employ a water cooled, non-consumable electrode, made of copper, tungsten, etc., as a pilot electrode. The pilot electrode is positioned substantially normal to the molten surface and is so mounted that its end is fixed relative to the discharge end of the surface fusing

electrode. That is to say, the pilot electrode is fixedly positioned relative to and vertically movable with the welding head of the surface fusing electrode or some element thereof such as the contact nozzle, electrode feed wheels, etc., that by its vertical movement raises the end of the electrode. By discharging electric current from the ends of the pilot electrode against the surface of the molten metal and by vertically moving the pilot electrode as required to maintain the length of the discharge constant, the end of the surface fusing electrode is maintained in a fixed positional relation with the surface of the molten metal. The arc length of the pilot electrode 10 may be controlled manually or automatically. In the manual control the voltage of the discharge is indicated and the pilot electrode is manually raised to maintain the voltage indication substantially constant. In the automatic control any of the usual arc control arrangements may be associated with the circuit of the pilot electrode and these employed to control the operation of a motor that is arranged to raise the electrodes and their associated mechanisms.

25 The apparatus of the drawings is particularly suited for carrying out the novel method and can be used both in the formation of metal bodies in which molten metal is deposited around a cylinder of solidified metal, or, around or within a shell of solidified metal. The apparatus can equally well be used when the molten metal is deposited against a flat surfaced solidified metal body by merely eliminating or not using the rotatable mold stand.

30 35 The apparatus of Figs. 1 and 2 is arranged for manual raising of the welding head while that of Fig. 3 is arranged for the automatic raising of the welding head; otherwise the showings and the apparatus of these figures are identical.

40 The welding head 10 is mounted for vertical movement relative to a frame 11. Frame 11 is attached to platform 12, see Fig. 2, which is supported for horizontal movement back and forth on bridge 13. Bridge 13 is supported by structural members 14 at a convenient distance from the floor of a structure housing the apparatus.

45 Platform 12 may be moved back and forth along bridge 13 manually or, as shown, a motor 15 may be provided for this purpose. Motor 15 is of the reversible type and is preferably of variable speed. The ends of the drive shaft of motor 15 carry pinions 16 that engage racks 17 fastened to the members of bridge 13. Platform 12 is usually employed to support electrode reels, material supply devices, etc., which of themselves do not form a part of this invention and have for this reason not been shown.

50 Adjacent the upper end of frame 11 is supported, in suitable bearings, a shaft 18 that carries at each of its ends a sprocket wheel 19. A similar shaft 20 and sprocket wheels 21 are positioned adjacent the lower end of frame 11. A worm wheel 22 is provided on shaft 20 adjacent one of sprocket wheels 21. Wheel 22 meshes with a worm 23. In Figs. 1 and 2 worm 23 is driven by handwheel 24 which is supported on frame 11, while in Fig. 3 worm 23 is carried at the end of the drive shaft of a motor 25. Motor 25 is likewise supported on frame 11 and is of the vari-speed reversible type generally used for feeding welding electrodes. Chains 26 and 27 run over sprocket wheels 19 and 21. One end of each of the chains is fastened to the top of welding head 10 while the other end of each of

the chains is fastened to the bottom of welding head 10. Thus, by rotating hand-wheel 24 of Figs. 1 and 2 or by energizing motor 25 of Fig. 3, welding head 10 may be raised or lowered. Rollers 29 carried by welding head 10 and bearing on frame 11, are provided to maintain welding head 10 against lateral movement and to facilitate the vertical movement thereof.

5 10 Welding head 10 is diagrammatically represented and is intended to include the current supply connections or generators, the feed motors, control arrangements, etc., for the electrodes to be described hereinafter. The electrode feed motors, the control arrangements, etc., included in head 10 may be of any preferred kind, well known in the electric arc welding and the electric arc furnace arts, suited for the purpose. The elements constituting the head may be of comparatively simple form as shown for instance in the Morton Patent No. 1,648,561 or they may be of more complicated form as shown for instance in the Kennedy et al. Patent No. 2,145,010. Since the invention is not dependent on any specific form of welding head no specific form of welding head is shown or described here. A 15 panel 30 is attached to and depends from head 10. Panel 30 has mounted thereon apparatus elements to be hereinafter described.

20 25 Positioned beneath head 10 is a rotatable mold stand 31 in which is supported an annular shell 32 30 of solidified metal.

30 35 Adjacent one end of head 10 is a pair of guide rollers 33 that guide the surface fusing electrode 34 to the feed rollers 35 from whence it passes through contact and bending nozzle 36. Rollers 35 are operated by a feed motor 37 that, as shown, is supported from panel 30 adjacent nozzle 36. Motor 37 is controlled from arc control arrangements of the usual sort to maintain an electric discharge from the end of electrode 34 40 of desired characteristics. Motor 37 is preferably located close to nozzle 36, as shown, to assure an uninterrupted feed. One side of the current supply is connected through cable 38 to nozzle 36, the other side is connected through cable 39 to 45 ground cable 40.

40 45 By rotating shell 32 electrode 34 will fuse a band of the surface of shell 32. With shells of comparatively small diameter the fused band will be sufficiently continuous to assure a union 50 throughout with molten metal 41. However, when the size of the shell increases a plurality of electrodes 34 may be necessary. Two electrodes 34 spaced 180° apart are shown in the drawings, however, when required a greater number spaced apart as necessary, may be used.

50 55 Nozzle 36 as shown, bends electrode 34 from the vertical towards the surface of shell 32. The arc control arrangements mentioned while they will be effective to maintain a substantially constant discharge will not maintain the end of the electrode in a fixed positional relation with the rising level of molten metal 41 and the surface of shell 32. Unless such fixed positional relation is maintained the discharge will move so far 60 away from the surface of shell 32 as to be ineffectual for the intended purpose. Also, eventually the molten metal will contact nozzle 36.

60 65 In order to maintain the fixed positional relation mentioned, non-consumable pilot electrode 70 42 is provided. Electrode 42 includes a body made of copper or other suitable material that is provided with a passageway through which water or similar medium may be circulated. The water is led to the body through valved line 43 75

and returned through valved line 44. Electrode 42 is fastened to the end of rod 45 which is adjustably supported in brackets carried by head 10 and panel 30. Current may be supplied to electrode 42, from a suitable source through cable 46, the other side of the current source may be connected to ground cable 40 by cable 47.

In the embodiment of Figs. 1 and 2 volt meter 48 is provided on head 10 to indicate the voltage 10 of the arc between electrode 42 and the molten metal, or when flux blanket 49 is molten, between electrode 42 and the molten flux. Thus, by manipulation of hand wheel 24 head 10 and all of the elements and mechanisms carried thereon 15 may be raised as required to maintain a predetermined discharge at the end of electrode 42. This will necessarily maintain a predetermined distance between the end of electrode 34 and the molten metal.

20 In the circuit of electrode 42 of Fig. 3 are included arc control arrangements that control the operation of motor 25. These arc control arrangements may also be of any preferred kind suited for the purpose and for example may be 25 of the character shown in the Morton Patent No. 1,648,561 or the Kennedy et al. Patent No. 2,145,010. In this case motor 25 will operate to raise head 10 and all carried by it as required to maintain the predetermined discharge from 30 the end of electrode 42 and thus, maintain the end of electrode 34 a predetermined distance from the molten metal.

Molten metal 41 may be supplied in whole or in part from an external molten metal source 35 such as a furnace, etc. Metal from such source, in the apparatus shown, is poured from ladle 50 through conduit 51 through flux 49. The molten metal may also be bottom poured, i. e. it may be poured through a suitable conduit that opens in 40 the bottom of the mold.

Molten metal 41 may also be supplied in whole or in part from a plurality of consumable electrodes 52, only one being shown. Electrodes 52 may be solid or hollow and of any preferred 45 cross-section, if desired constituents of molten metal 41 may be fed through electrodes 52 when they are hollow.

50 Electrode 52 is fed by means of feed wheels 53 through contact nozzle 54 toward the surface of metal 41. The feed motor actuating feed wheels 53 is controlled by the usual arc control arrangements to maintain a discharge of predetermined characteristics. Current is supplied from a suitable source to contact nozzle 54 by cable 55. The other side of the supply is connected to ground cable 40 by cable 56.

Mold stand 31 includes a bottom support element 57 which carries a plurality of support rollers 60 and 61, two only being shown. In the 60 center of element 57 is provided a cavity into which is fitted thrust bearing 62 that supports hollow shaft 63 for rotation about a vertical axis. Shaft 63 is attached to cylindrical block 64 and has splined thereto ring gear 65. A bearing disc 65 66, against which rollers 60 bear, is also splined on shaft 63. Gear 67, that is driven by the output shaft of transmission box 68, meshes with ring gear 65. Transmission box 68 is preferably of the multi-ratio type and is driven by motor 70 69. Block 64 includes a contact ring 70, of copper or similar material, against which bear contact brushes 71. Ground cable 40 is connected to brushes 71.

Block 64 has a central bore 72 therein that registers with the bore of shaft 63. Bore 72 is

enlarged at its upper end and communicates to the outside of block 64 by means of radial bore 73. A pipe 74 is concentrically located within bore 72 and the bore of shaft 63 and screws into block 64. Pipe 74 communicates to the outside of block 64 by means of a radial bore 75. The lower end of the bore of shaft 63 is closed by a gland 76 that surrounds a hollow fitting 77 through which pipe 74 extends. Fitting 77 is fixed against rotation and has a valved water exit line 78 screwed into it. Into the end of fitting 77 is screwed a second fitting 79 into which pipe 74 opens. A valved water inlet line 80 screws into fitting 79.

15 Circular mold stand 31 is positioned concentrically upon block 64. Mold stand 31 may be permanently or removably fastened to block 64. As shown, mold stand 31 includes a plurality of connected passageways 82 through which water or similar medium may be circulated for the cooling of mold stand 31 and thus aid in the control of the penetration into the metal of shell 32. Passageways 82 need not be incorporated in mold 81 but in lieu thereof mold 81 may include a jacket through which the cooling medium is circulated. As shown the inlet of passageways 82 is connected to bore 75 by pipe 83 and the outlet of passageways 82 is connected to bore 73 by pipe 84.

20 I claim:

1. In apparatus of the character described, a surface fusing electrode, means for directing said electrode toward a metal surface angularly disposed to the horizontal, means for depositing molten metal against said metal surface to progressively cover said surface, means for maintaining an electric discharge of desired characteristics between said electrode and the zone of the meeting line of said molten metal and said surface, a non-consumable electrode adapted to discharge electric current against said molten metal fixedly positioned relative to said directing means and vertically movable therewith, and means for moving said non-consumable electrode and said directing means to maintain a discharge of substantially constant characteristics from the end of said non-consumable electrode and to maintain a substantially constant positional relation between the end of said surface fusing electrode and the surface of said molten metal. 25

2. In apparatus of the character described, an electrode, means for directing said electrode toward a metal surface angularly disposed to the horizontal, means for depositing molten metal against said metal surface to progressively cover said surface, means for maintaining an electric discharge of predetermined characteristics between said electrode and the zone of the meeting line of said molten metal and said surface and means for raising said electrode to maintain a substantially fixed positional relation between said electrode and the surface of the molten metal. 55

3. In apparatus of the character described, an electrode, means for directing said electrode toward a metal surface angularly disposed to the horizontal, means for depositing molten metal to progressively cover said surface, means for maintaining a discharge of desired characteristics between said electrode and the zone of the meeting line of the molten metal and said surface to fuse said surface, means for effecting movement between said electrode and said surface to fuse a band of said surface, and means operative to vertically move said electrode to maintain a sub- 60 65 70 75 80 85 90 95 100

stantially fixed positional relation between the surface of the molten metal and the end of said electrode.

4. In apparatus of the character described, a 5 rotatable mold, means for rotating said mold about a substantially vertical axis, said mold being adapted to receive therein a workpiece having a cylindrical surface disposed substantially concentrically to said axis, means for depositing 10 molten metal in said mold to progressively cover said cylindrical surface, electrode means adapted to discharge electric current in the zone of the meeting line of the molten metal and said surface, means for passing current to 15 said electrode means, means for passing current to said mold, and means for maintaining said electrode means in a substantially fixed positional relation with the surface of the molten metal as it rises in said mold.

20 5. In apparatus of the character described, a consumable electrode adapted to deposit metal by electric discharge to progressively cover an angularly disposed metal surface, electrode means adapted to discharge electric current in the zone 25 of the meeting line of the molten deposited metal and said metal surface to fuse metal of said surface and unite the metals, a non-consumable electrode adapted to discharge electric current against the surface of the molten metal, said 30 consumable electrode, said electrode means and said non-consumable electrode being mounted for unitary vertical movement, and means for moving said consumable electrode, said electrode means and said non-consumable electrode vertically 35 as a unit to maintain a predetermined distance between said non-consumable electrode and the surface of the molten metal.

6. In apparatus of the character described, 40 electrode means adapted to discharge electric current to fuse metal of the surface of a workpiece that is disposed at an angle to the horizontal, a second electrode means adapted to discharge electric current against a substantially horizontal surface to deposit metal to progressively cover said first mentioned surface, a non- 45 consumable electrode adapted to discharge electric current against the rising surface of the deposited metal, said non-consumable electrode, said second electrode means and said first electrode means being mounted for vertical movement as a unit, means for indicating the characteristics of the discharge from said non-consumable electrode, and means for vertically moving said non-consumable electrode, said second electrode 50 means and said first electrode means as a

unit to maintain the discharge from said non-consumable electrode at established characteristics.

7. In apparatus of the character described, 5 electrode means adapted to discharge electric current to fuse the surface of a workpiece that is disposed at an angle to the horizontal, a second electrode means adapted to discharge electric current against a substantially horizontal surface to deposit metal to progressively cover 10 said first mentioned surface, a non-consumable electrode adapted to discharge electric current against the rising surface of the deposited metal, said non-consumable electrode, said second electrode means and said first electrode means being 15 mounted for vertical movement as a unit, motor operated means for vertically moving said non-consumable electrode, said second electrode means and said first electrode means, vertically 20 as a unit, and control means for said motor operated means operative to control the operation of said motor operated means to maintain a discharge of predetermined character from said non-consumable electrode.

8. In apparatus of the character described, 25 electrode means adapted to discharge electric current to fuse the surface of a workpiece that is disposed at an angle to the horizontal, a non- 30 consumable electrode mounted for vertical movement as a unit with said electrode means adapted to discharge electric current against a substantially horizontally disposed surface, means for indicating a characteristic of the discharge from the non-consumable electrode, and means for vertically moving said non-consumable electrode 35 and said electrode means as a unit to maintain the indicated characteristic at a predetermined value.

9. In apparatus of the character described, 40 electrode means adapted to discharge electric current to fuse the surface of a workpiece that is disposed at an angle to the horizontal, a non- 45 consumable electrode mounted for vertical movement as a unit with said electrode means adapted to discharge electric current against a substantially horizontally disposed surface, controllable motor operated means for vertically moving said electrode means and said non-consumable electrode as a unit, and means controlling said motor operated means in accordance with the characteristics of the discharge from said non-consumable electrode to maintain said discharge at a 50 predetermined value.

ROBERT K. HOPKINS. 55
